INVENTOR:

UNITED STATES PATENT OFFICE.

WILLIAM L. DEMING, OF SALEM, OHIO.

DESIGN FOR A SCORE-CARD.

43,402.

Specification for Design.

Patented Dec. 31, 1912.

Application filed September 6, 1912. Serial No. 719,038. Term of patent 14 years.

To all whom it may concern:

Be it known that I, WILLIAM L. DEMING, a citizen of the United States, residing at Salem, in the county of Columbiana and State of Ohio, have invented a new, original, and ornamental Design for Score-Cards, of which the following is a specification, reference being had to the accompanying drawing, forming part hereof.

The drawing is a plan of the score card showing my new design.

I claim:

The ornamental design for a score card as shown.

WILLIAM L. DEMING.

Witnesses:

ALBERT H. BATES,
WALTER D. AMADEN.
